UNITED STATES PATENT OFFICE

2,328,145

COLOR TELEVISION

Bertram Tom Hewson, London, England

Application August 20, 1941, Serial No. 407,537
In Great Britain June 15, 1939

1 Claim. (Cl. 178—5.2)

In my co-pending patent applications Serial Nos. 360,352, 360,353 and 360,354, I have described and claimed certain methods of producing colored images which are applicable to color television. The present invention is concerned with certain modifications of the methods of color television described in my said co-pending patent application, and has for its chief object to provide a simple system of color television.

According to the principal feature of the present invention, an independent scanning beam is used for each of the color elements which it is desired to reproduce in the viewed image.

Over the image plate of the usual electron camera is disposed a multi-colour mosaic line screen between which and the line plate is arranged a mica plate or like insulating element. Instead of a single line plate, as is usual in monochromatic television, a multi-line plate is provided, each of the line sections corresponding to one of the colors of the system.

In order that this invention may be the more clearly understood and readily carried into effect, I will proceed to describe the same with reference to the accompanying drawing, which illustrates by way of example certain embodiments of this invention, and in which:

Figure 1 is a diagrammatic view of part of the transmitting apparatus according to the present invention as applied to a four-color system.

Figure 2 is an enlarged section through the image plate shown in Figure 1.

Figure 3 is a diagrammatic view illustrating one method of producing a multi-section line plate for use in the apparatus shown in Figure 1.

Figure 4 illustrates part of a receiving apparatus according to the present invention adapted for direct viewing, and

Figure 5 illustrates a similar apparatus by means of which the image may be projected on to a screen.

Referring now to the drawing, it will be seen that for the sake of clarity the actual amplifying, transmitting and receiving apparatus has not been shown in the drawing. Such apparatus may follow standard practice and detailed description of the same is deemed to be unnecessary.

The drawing indicates the present invention as applied to a four-color system of television and the electron camera (Figure 1) is provided with four independent scanning beams shown in broken lines provided by four independent cathodes shown diagrammatically at 11, 12, 13 and 14.

Over the image plate is disposed a four-color line screen which consists of a transparent plate 15, a mica plate or the like 16 and a mosaic metal coating 17 arranged between said transparent plate 15 and said mica plate 16. Instead of a single line plate, as is usual in monochromatic television, a four-line plate 18 is provided, each line extending from side to side of the surface and the lines being correlated with the lines of the mosaic color line screen so that each of the line sections corresponds to one of the colors (see Figure 2).

A multiple line plate 18, as above described, may be formed of the appropriate number of sheets of tin foil 20 appropriately insulated from one another and folded backwards and forwards, as shown in Figure 3. The folds are pressed together and clamped edgewise against the mica plate 16 in register with the mosaic screen. Alternatively, the same may be produced photographically, or in any other desired manner. Each of the line sections of the plate 18 is fed to a separate amplifier and modulator or transmitter by means of the independent lines 21, 22, 23 and 24 so that the individual color impulses may be selectively transmitted by the transmitter and received at the receiver.

A similar arrangement is used at the receiver (see Figures 4 and 5), the individual cathode ray beams 30, shown in broken lines and provided by individual cathodes, being modulated in accordance with modulation effected for the individual colors of the image at the transmitter in the usual way. The image at the receiver may be viewed directly on the fluorescent screen 29 without the aid of auxiliary light, as shown in Figure 4, in which the lens unit 31 may, if desired, be omitted. Alternatively, an auxiliary light from a source 32 may be passed through the mosaic color line screen, as shown in Figure 5. The mosaic screens used at the transmitter and receiver are, of course, identical and suitably positioned relative to the image-receiving screen in both cases and, accordingly, like references have been used in Figures 4 and 5 to indicate the parts corresponding to those shown in Figure 1.

At the transmitter, the color line screen acts in co-operation with the colored image of the object or scene being televised in the same way as in color photography or cinematography to filter out the colors. Thus green light from the object or scene will be stopped by the red line of the screen (if it be complementarily colored), and no image will be thrown on to the particular

line of the line plate 18 at this point. There will thus be no modulation of the corresponding transmitted frequency. At the receiver, the color line screen acts in the same way as a similar device in a like system of color cinematography.

I claim:

A multi-color television system, comprising a transmitter and a receiver, each having means for using an independent individually controlled scanning beam for each of the separate colors

of the system, image plates at the transmitter and the receiver including like multi-color mosaic line screens, a multi-element line plate at the transmitter, said multi-element line plate having one element for each color, and an auxiliary source of light at the receiver to pass light through the mosaic line screen at the receiver in order to render the image visible.
